UNITED STATES PATENT OFFICE.

HENRY W. PELL, OF ROME, NEW YORK.

IMPROVED DIES FOR FORMING THE HEADS OF WRENCHES.

Specification forming part of Letters Patent No. **56,602**, dated July 24, 1866.

To all whom it may concern:

Be it known that I, HENRY W. PELL, of Rome, in the county of Oneida and State of New York, have invented new and useful Improvements in the Manufacture of Wrenches; and I do hereby declare that the following is a full, clear, and exact description thereof, which will enable others skilled in the art to make and use the same, reference being had to the accompanying plate of drawings, forming a part of this specification.

The present invention consists in subjecting a straight bar of iron, of the requisite length, width, and thickness, to the action of a series or set of dies, by which a head and shoulder, similar in shape to the ordinary heads of wrenches, are formed thereon, and the full strength of the iron retained.

In accompanying plate of drawings a set of dies, by which a wrench-head is formed from and upon a bar of iron of the requisite dimensions, is illustrated, each die of the set being numbered upon the said plate in the order in which they are used.

In using the set of dies represented in the drawings a bar of iron, of about two inches in width and seven-eighths of an inch in thickness and four and a half inches in length, is first taken and rolled into the shape at one end (shown in Figure 1 of the drawings) by passing it through any suitable rolling-mill therefor, when, laying it on the lower die, A, of the first one of the series, it is then subjected to the action of its upper die, B, until sufficiently hammered thereby into a shape corresponding to such die. The bar thus hammered is then removed from such die and

placed in the next one of the series, numbered 2 in the drawings, and by it hammered into a shape corresponding thereto, when, removing the bar therefrom, and in turn subjecting it to the actions of the dies numbered 3 and 4 in the drawings, the bar, when removed from the latter, will have the requisite head and shoulder thereon, corresponding to the ordinary wrench-heads, as is plain to be seen in the lower view of the last die, the bar of iron, however, previous to being inserted in die numbered 3 in the drawings, being laid by its flat side upon the lower portion of die No. 1, across the notch *a* of the same, and then subjected to the upper portion of the said die, by which it is perfectly prepared for dies Nos. 3 and 4, the shape given to such bar thereby being shown in Fig. 2 of the drawings.

By thus forming a wrench-head it is obvious that the full strength of the iron is retained, and a wrench secured possessing many superiorities over similar wrenches made in the ordinary manner.

I claim as new and desire to secure by Letters Patent—

The improvement in the manufacture of wrenches herein described, the same consisting in subjecting the bar of iron from which the wrench is to be made to the action of the consecutive set of dies, substantially as described, and in the manner and for the purpose set forth.

HENRY W. PELL.
